UNITED STATES PATENT OFFICE.

JACOB BURKHART, OF ELMHURST, PENNSYLVANIA.

BARRETTE.

Application filed June 18, 1925. Serial No. 38,048.

My invention aims to provide a new and improved form of barrette for use to hold bobbed hair in orderly fashion at the sides of the head, the device being of such nature as to prevent separation of strands of the hair, for instance, when leaning forwardly.

With the foregoing in view, the invention resides in the novel subject matter herein-after described and claimed, the description 10 being supplemented by the accompanying drawing.

Figure 1 is a perspective view showing the application of the invention.

Figure 2 is a perspective view of the 15 barrette with the greater part of its ornamental covering removed.

Figure 3 is a transverse sectional view on line 3—3 of Fig. 2.

In the drawing above briefly described, the 20 numeral 1 designates a U-shaped spring which is preferably formed of a thin flat strip of metal bent into the proper shape. For future reference, one arm of the spring 1 is designated by the numeral 2 and the 25 other arm of said spring is identified by the numeral 3. An elongated plate 4, preferably formed of sheet metal, is secured by soldering, brazing, riveting or in any other preferred manner to the arm 2 of the spring 30 1, said plate projecting throughout the greater portion of its length from said spring, in the direction in which the arm 2 projects, while one end of said plate indicated at 5, projects a slight distance in the opposite direction from the spring. Preferably, the 35 plate 4 is provided with a thin ornamental covering 6 of any desired material, such as celluloid.

Secured to the arm 3, I have shown two 40 fingers 7 which may be formed of wire or any other desired material, said fingers being integrally connected at one end, as indicated at 8, while their opposite ends 9 are free of connection. These ends 9 project 45 from the spring 1 in the same direction in which the arm 3 projects, while the finger-connecting portion 8 projects a slight distance from said spring, in the opposite direction, forming a finger-piece which is

adapted to be moved toward the rear end 5 50 of the plate 4 thus effecting separation of the fingers from the plate and permitting the device to be readily applied to or removed from the hair.

Preferably, the fingers 7 are of serpentine 55 formation to prevent easy withdrawal from the hair, and I also prefer to provide the greater portion of the plate 4 with a longitudinal rib 10 at its inner side, to force the hair between the fingers and co-operate with the latter in tenaciously holding the barrette in any position at which it may be applied. The rib 10 may well be formed by stamping the plate 4, as will be clear from Fig. 3.

It will be seen from the foregoing that 60 the device is simple and inexpensive, yet that it will be very desirable, may be quickly and easily applied or removed, and will hold the hair in the desired orderly fashion at one or both sides of the head, as occasion may 65 demand.

As excellent results are obtainable from the details disclosed, they may well be followed. However, within the scope of the invention as claimed, modifications may of 70 course be made.

I claim:

A barrette comprising a U-shaped spring, an elongated plate secured to one arm of said spring and projecting throughout the greater part of its length from said spring in the direction in which said arm projects, said plate projecting slightly in the other direction from the spring, and a pair of fingers secured to the other arm of said spring and 80 projecting throughout the greater part of their lengths from the spring in the direction in which said other arm projects, the inner ends of said fingers projecting slightly 85 from the spring in the opposite direction, the major portions of said fingers being of serpentine form, the major portion of said plate having a longitudinal rib on its inner side to force the user's hair between said fingers. 90

In testimony whereof I have hereunto affixed my signature.

JACOB BURKHART.
